CAR TRUCK

Robert B. Cottrell, Chicago, Ill., assignor to American Steel Foundries, Chicago, Ill., a corporation of New Jersey

Application September 29, 1950, Serial No. 187,409

2 Claims. (Cl. 105—197)

This invention relates to railway car trucks.

A primary object of the invention is to devise a novel truck comprising simplified side frames and bolster to obtain a light weight exceptionally strong construction which may be easily assembled and disassembled.

A further object of the invention is to provide novel side frames of a beam type wherein the various sections are formed and arranged to provide an enclosure for the bolster supporting springs and guides for the bolster and at the same time afford an exceptionally strong construction.

In several embodiments of the invention, friction means are incorporated for controlling relative movements between the bolster and side frames at opposite sides of the truck and to damp spring oscillations.

These and other objects of the invention will become more apparent from the specification and the drawings, wherein:

Figure 1 is a fragmentary composite side elevational view of one form of the invention, the right half of the view being an inboard elevational view of the side frame and cross sectional view of the bolster, the left half being an outboard elevational view of the side frame and the bolster;

Figure 2 is a fragmentary top plan view of the truck with the bolster at the right half removed;

Figure 3 is a sectional view taken substantially on the line 3—3 of Figure 1, the bolster being shown in side elevation;

Figures 4 and 5 illustrate another embodiment of the invention, Figure 4 being the fragmentary side elevational view thereof, and Figure 5 being a fragmentary top plan view thereof; and

Figures 6 and 7 illustrate a further embodiment of the invention and are comparable to Figures 4 and 5 respectively.

Describing the invention in detail and referring first to the embodiment shown in Figures 1 to 3, the truck comprises a side frame at each side in the form of a beam type member 2, said member having a depressed central portion, generally indicated 4, and upwardly diverging end portions, generally indicated 6, 6. The side frame comprises a bottom transverse web 8, which extends substantially horizontal in the central portion of the frame and diagonally upwardly at the end portions of the frame, and merges at its ends into the inboard sides of journal boxes 10, 10 diagrammatically illustrated. The wall 8 is joined at its lateral edges to the bottom edges of substantially vertical inboard and outboard walls 12 and 14. The side walls are joined at their upper edges at the end portions of the frame by upwardly sloping transverse webs 16, 16, which are convexed upwardly in the regions immediately adjacent to and above the journal boxes. The top walls 16 are bifurcated as at 18 at the ends of the frame and terminate with the side walls 12 and 14 at the outboard sides of the journal boxes. It will be seen that the side walls 12 and 14 merge with the inboard sides of the journal boxes adjacent to their upper ends

2

and with the top sides of said boxes. The journal boxes 10 are shown only in outline form inasmuch as they are of conventional design such as presently used in railway service.

5 The upper edges of the side walls 12 and 14 at the central zone of the side frame are connected to a spring seat wall 20, said wall 20 being slightly widened and extending a small distance inboardly and outboardly of the walls 12 and 14. The inboard and outboard edges of the wall 20 merge into lower edges of substantially vertical inboard and outboard webs 22 and 24, said webs 22 and 24 extending lengthwise longitudinally of the side frame and curving at their ends into the adjacent portions of the inboard and outboard walls of the end portions 15 6, 6 of the frame.

The wall 20 comprises a lower or depressed portion 26 centrally thereof and a stepped-up end portion 28 at each end thereof. The portion 26 is flanged upwardly as at 30 at each end and merges with the adjacent end of portion 28, and the outer end of each portion 28 is formed with an upwardly extending flange 32 which joins the inboard and outboard webs 22 and 24. The upper ends of webs 22 and 24 are provided with outturned flanges 34 and 36, said flanges strengthening the construction and at their ends tapering into the inboard and outboard walls 12 and 14 of the end portions in the areas of the inner ends of walls 16, 16. Thus it will be seen that the construction of the webs 22 and 24 and the wall 20 forms a convenient deep spring pocket 38. The webs 22 and 24 20 and their slight spacing inboardly and outboardly of the walls 12 and 14 and their merger at opposite ends with the inner ends of the end portions materially strengthen the central portion of the side frame and its juncture with the end portions of the frame. The stepped arrangement of the spring seat wall also strengthens the central zone of the frame.

The central zone 4 of the frame is provided on its top side at opposite ends of the spring seat with upstanding extensions, generally indicated 40, 40. Each extension 40 comprises an upright arcuate web 42, presenting a curved guide surface 44 facing toward the center of the frame. The lower edge of each web 42 merges in the area between the planes of the walls 12 and 14 with the inner end of the adjacent wall 16. The lateral end portions of the wall 42 are continued at their lower edges for a short distance on the top sides of the substantially horizontal flanges 34 and 36. The lateral edges are flanged outwardly as at 46 and 48 and tapered downwardly. The outer side of each web 42 is formed at its 45 crest integral with a vertical edge of a gusset 50, the lower edge of the gusset merging with the top side of the adjacent web 16. Each gusset 50 is positioned substantially centrally between the inboard and outboard sides of the related end portion 6.

55 A group of coil springs 52, 52 is disposed within the pocket 38. As herein shown, two sets of springs 52, 52 are seated at their lower ends on portion 26 of web 20 and one set of springs 52 is seated on each portion 28.

All of the sets of springs 52, 52 are of substantially 60 equal height and the central sets of springs seat against a bottom wall 54 of a bolster, generally indicated 56. Each end set of springs 52 seats against a bottom web 58 of a transversely extending wing 60 on the adjacent side of the bolster. The wall 58 of each wing 60 is offset upwardly with respect to the wall 54 and is flanged at its inner end as at 62, the flange 62 merging at its lower lateral edge with the bottom wall 54. The outer edge of the wall 58 is connected to a top wall of the wing and bolster by a peripheral wall 64, said wall 64 in the area 65 adjacent to the guide surface 44 having an outer guide surface 66 concentric with the adjacent surface 44. The wall 64 is cut out at the outboard end of the bolster as 70

at 68 for convenient foundry practice and to reduce weight. The wall 64 extends below the wall 58 and affords a convenient pocket for the upper end of the associated end set of springs 52. The inboard end of the wall 64 merges into an adjacent side wall 71 of the bolster, said side walls interconnecting the bottom wall 54 of the bolster with the top wall 72 of the bolster, the top wall 72 extending at opposite sides of the bolster and merging with the inner edge of wall 64.

The top and bottom walls 72 and 54 of the bolster are interconnected substantially centrally thereof by a substantially vertical center rib 74.

The bolster is provided adjacent each end on the top side thereof inboardly of the frames with an upstanding side bearing 76.

Assembly of the bolster and the side frame is maintained by stop means at the upper ends of the extensions 40, said stop means comprising bolts 78 arranged to have their heads for abutment with the top sides of the wings 60. This feature permits lifting the bolster and the side frames together.

The side frame is provided at each side of its central zone with brake beam support brackets, generally indicated 80. Each bracket is formed integral with the inboard wall 12 and comprises top and bottom webs 82 and 84, interconnected by end webs 86 and 88, said end webs being disposed substantially perpendicular to webs 82 and 84 and defining a slot 90 therewith, the slot and the top and bottom webs being inclined upwardly toward the adjacent end of the frame. It will be noted that a longitudinal center line passing through the slot intersects the axis of the adjacent wheel and axle assembly. The bottom web 84 of each bracket is formed intermediate its ends integral with a gusset 92 which extends from the bottom side of web 84 and merges transversely with the inboard side of wall 12.

Referring now to the embodiment shown in Figures 4 and 5, wherein parts identical with previous embodiments are identified by corresponding reference numerals. The present embodiment differs from the previous in that each extension 40 is formed with a pocket 100, receiving a friction shoe 102. The pocket is formed with inboard and outboard ledges 104, 104 in wedge engagement with ledges 106, 106 at opposite sides of the shoe along upwardly sloping surfaces as at 108. The ledges 106, 106 of the shoe interconnect front and rear walls 110 and 112 of the shoe. The front wall has a substantially flat friction surface in engagement as at 114 with a friction plate 116 connected to a flat portion 118 of the wall 64. The shoe has a top wall 120 interconnecting the upper ends of the front and rear walls and providing a seat as at 122 for an actuating spring 124, the bottom end of the actuating spring seating as at 126 on a seat 128 which is formed as part of the inner end of the top wall 16 of the adjacent end portion 6. In the present modification, the wall 16 is offset downwardly at its inner end and merges with the upper edge of the adjacent flange 32.

The bolster and side frame are maintained in assembled relationship by stop means in the form of a bolt 130 which is secured to an outboard wall 132 of each extension 40. This extension 40 also has an inboard wall 134 which with the wall 132 embraces the adjacent wing 60 therebetween and affords guide means for the bolster.

Referring now to the embodiment shown in Figures 6 and 7, wherein parts similar to those shown in the previous embodiments are identified by corresponding reference numerals, it will be seen that in the present embodiment the construction differs only in the provision of a friction shoe in each side of the bolster. The extension 40 is formed as a flat web 200 extending substantially vertically transversely of the frame, the rear side of web 200 being connected to spaced inboard and outboard gussets 202, 202, the gussets 202 merging with the top side of wall 16 of the adjacent end portion 6. The bolster wing 60 is formed with a housing 204 extending upwardly from the

top of the bolster, the housing 204 receiving the upper end of a spring 206 which seats as at 208 against the underside of a top web 210 of the housing. The spring 206 extends into a shoe 212, similar to shoe 102, and seats at its lower end against a bottom wall 214 as at 216. The shoe comprises a ledge 218 at each side thereof in slidably engagement with ledges 220, 220 formed in the related wing on the inboard and outboard walls 222 and 224 thereof. The ledges 218 interconnect front and rear walls 226 and 228 of the shoe which at their lower edges are interconnected by the bottom wall 214. The shoe 212 is urged downwardly on its ledges 218, 218 along the related ledges 220, 220 to engage a friction surface 230 on a friction panel 232 mounted in any convenient manner such as by welding on the web 200.

The bolster and the side frame are maintained in assembled relationship by means of a stop 234 on each guide 40 and secured to the outboard gusset 202 of each extension, the stop means 234 being in the form of a bolt having a head overlapping an extension 236 of an outboard wall of the related wing 60.

It will be realized that in each embodiment a simple truck structure is provided which may be readily assembled and disassembled by removing the stop bolts on the frame which engage the upper side of the bolster.

I claim:

1. In a railway car truck, a one-piece cast steel side frame comprising a single beam member having a substantially horizontal central portion and upwardly diverging end portions, journal boxes at the remote extremities of said end portions, said central portion having a spring seat comprising a horizontal wall extending slightly beyond the inboard and outboard sides of said beam member, said seat having stepped-up portions at opposite ends, inboard and outboard upstanding walls connected at their lower ends to the inboard and outboard edges of said wall and curved toward each other at opposite ends and merging into the inboard and outboard sides of the end portions, substantially vertical extensions at opposite ends of said central portion projecting upwardly therefrom, each extension comprising a wall, a bolster having ends disposed between said extensions, means on the bolster and extensions for guiding movement of the bolster, removable stop means connected to said extensions for abutment with the top side of said bolster for maintaining the bolster and side frame in assembled relationship, whereby the same may be handled as a unit for quick wheel change, a plurality of springs on the seat of substantially equal height and supporting the bolster, said bolster having a central portion and upwardly offset portions at opposite sides of said central portion, all of said portions of the bolster seating on said springs, and walls on said upwardly offset portions of the bolster surrounding the upper extremities of the springs seated thereagainst.

2. In a one-piece cast steel side frame for a railway car truck, a beam comprising a single member having a central substantially horizontal portion and upwardly diverging end portions, all of said portions comprising common inboard and outboard walls and a bottom wall, a spring seat wall medially disposed between the top and bottom edges of said central portion, said spring seat wall comprising two end sections at opposite ends of said central portion and a central section between and below said end sections, said central section being joined at opposite ends to the adjacent ends of the end sections by upwardly extending flanges, said end portions being provided at their remote ends with upwardly extending flanges, said spring seat wall and the flanges thereof extending transversely of the beam member and interconnecting said inboard and outboard walls, upstanding inboard and outboard walls at the inboard and outboard edges of said spring seat wall, said inboard and outboard walls extending between the inner extremities of said end portions and merging with the inboard and outboard walls thereof.

said walls and said seat providing a spring pocket, and bolster guide extensions on opposite ends of said central portion and projecting upwardly therefrom.
